UNITED STATES PATENT OFFICE.

WILLIAM N. DARNEll, OF WORTHINGTON, INDIANA.

SHINGLE-MACHINE.

SPECIFICATION forming part of Letters Patent No. 403,420, dated May 14, 1889.

Application filed May 28, 1888. Serial No. 275,340. (No model.)

To all whom it may concern:

Be it known that I, WILLIAM N. DARNEll, a citizen of the United States, residing at Worthington, in the county of Greene and 5 State of Indiana, have invented certain new and useful Improvements in Shingle-Machines; and I do hereby declare the following to be a full, clear, and exact description of the invention, such as will enable others 10 skilled in the art to which it appertains to make and use the same.

Figure 1 is a side elevation of the machine, showing a single knife. Fig. 2 is a top plan with the top of frame of knives and rollers removed, showing a double set of each; Fig. 15 3, a top plan view, the top of the knife-frame removed, showing a single set of each; Fig. 4, enlarged top plan view of journal-block guides and spring on the roller. Fig. 5 is a 20 detail top plan of the frame. Fig. 6 is a detail side elevation of one of the rollers with its journal-block and guide-rods. Fig. 7 is a detail side elevation, enlarged, to show the jointing-knife, &c.

25 The object of this machine is to shave the sides of shingles which have been previously split with the grain of the wood or sawed, and joint the edges at the same time; and the novelty consists in the construction and combination of the several parts of the machine, all as will now be more fully set out and described.

In the accompanying drawings, A denotes 35 the bench or any suitable frame to support the parts of the machine. At each end of the top part of this bench are secured the upright guides B, which are so made that the sliding bar C can be easily and freely moved to and fro through them and over the top of 40 the frame or bench. In the depressions or seats c in each end of this bar, but on opposite sides, a bed-block, D, is placed so that it will be below the level of the surface of the bar, and by the formation of each depression 45 will be placed at a slight angle with the length of the bar. The object of this peculiar arrangement of the block is that when the piece of wood of which the shingle is made is placed in this depression against the 50 face of the bed-block and passed by the shaving-knife it will be cut thinner at one end than at the other. The face of this block is

made rough to prevent the shingle from slipping. This knife E is placed in a generally vertical position, but a little inclined with respect to the top of the bench and secured at top and bottom in the frame F, which is fixed to the top of the bench. In said frame are also journaled the vertical pressure-rollers G, and so placed that one, two, or more shall 55 come up on one side of the shingle as it passes the knife and one shall come on the outside of the bar. The single roller G, opposite the knife, is designed to prevent the slide from bending under the pressure of the rollers 60 near the knife. As the force of the springs is considerable, this result might otherwise follow. In the use of these rollers I do not wish to be limited to the exact number now shown, and in arranging them I wish to place them 65 at suitable points on opposite sides of the movable bar C, and in the construction of the said slide it is not absolutely necessary that it should be a solid bar. The first roller that presses against the shingle meets it as it approaches the knife, and the last roller continues the pressure so long as the shingle is in contact with the knife. The force of the pressure of said rollers is regulated by the 70 tension of the springs g, which act on their journals g' intermediately through blocks g², in which the journals move, and said blocks have guides g³ on each side; but I do not wish to be confined to this precise construction in applying the springs to the roller. 75

The rollers are actuated by springs, so as to yield to the inequality of the thickness, but at the same time to press firmly on the shingle to hold it in its place and also prevent the wood from so rising as to be cut in two. 80 While the rough shingle is passing the knife E and being shaved upon one side, its lower edge is jointed by means of the knife H, fixed in the bottom of the frame F and transversely thereto. When the shingle-piece has 85 been passed in one direction by one set of side and bottom knives, so as to be shaved and jointed on one side and edge, it can be removed from the face of the block D on that side of the bar and placed with its shaved 90 side against the block D on the other side, and then passed in the opposite direction between the spring-pressure rollers and against the knives that will operate on its other side 95 100

and edge, and at the completion of this operation comes out finished and ready for use.

The bar C may be moved by hand, by mechanism, or by power.

5 Instead of inclining the depression c, the block D may be so shaped as to accomplish the same ends.

Having now described my invention, what I desire to secure by Letters Patent is—

10 1. The movable bar C, having the inclined roughened-faced bed-block D in its side, combined with the guides B, the pressure rollers and springs acting on the journals of the same, and the inclined shaving-knife and the 15 jointing-knife, substantially as described.

2. The bench A, having guides B, and the frame F, the pressure-rollers G in said latter frame, also the shaving and jointing knives E and H, the movable bar C, having the inclined bed-block in its side, the said bar passing between said rollers, the pressure of the same being regulated by springs g acting on their journals through blocks g^2 moving in guides g^3 , substantially as described.

In testimony whereof I affix my signature in presence of two witnesses.

WILLIAM N. DARNELL.
